WESLEY G. NICHOLS, OF CHICAGO HEIGHTS, ILLINOIS, ASSIGNOR TO AMERICAN MANGANESE STEEL COMPANY, OF AUGUSTA, MAINE, A CORPORATION OF MAINE.

DIPPER-TOOTH.

1,242,715.

Specification of Letters Patent.

Patented Oct. 9, 1917.

Application filed February 17, 1915. Serial No. 8,746.

To all whom it may concern:

Be it known that I, WESLEY G. NICHOLS, a citizen of the United States, and a resident of Chicago Heights, in the county of Cook and State of Illinois, have made and invented certain new and useful Improvements in Dipper-Teeth, of which the following is a specification.

This invention relates to dipper teeth, 10 and more particularly to that class which are formed with removable points.

It has heretofore been found extremely difficult to prevent the jaws of the point from spreading, due to the severity of the 15 service to which the same is necessarily exposed, without excessively weakening the nose of the base. It has also been found, in some classes of dipper teeth, that the securing bolts are, in themselves, inadequate to 20 prevent this spreading of the point jaws, and it is therefore the object of the present invention to so form the nose and point, that the jaws will be positively held against spreading by the nose of the base, without 25 materially weakening the latter, and further, to so arrange the various parts, as to eliminate some of the securing bolts, and to materially reduce the strain to which 30 the other of the bolts are exposed.

A further object is to provide a dipper tooth including a base and a removable point, wherein the upper jaw of the point is provided with a lug which is substantially dove-tail in cross-section, and which 35 lug is of uniform thickness throughout, so that the holding action, between the lug and the undercut or dove-tail recess with which the base is provided and in which the lug seats, is not limited to one end of the lug, 40 but extends throughout the entire length thereof. In connection with the foregoing, there is provided a lug upon the lower jaw of the point which is of uniform width and thickness, and is accordingly directly insert- 45 ible within a recess in the lower portion of the tooth base; the holding action of the lower lug being supplemented by projecting the lower jaw of the point rearwardly and bolting, or in other ways securing, it 50 to the base.

Other objects and advantages will appear as the description proceeds, it being understood that changes in the precise em-

bodiment of the invention can be made within the scope of what is claimed, without departing from the spirit of the invention. 55

The preferred embodiment of my invention is disclosed in the accompanying drawings, wherein:—

Figure 1 is a view, in top plan, of a dipper tooth embodying the features of my invention; 60

Fig. 2 is a side view in longitudinal section thereof; 65
Figs. 3 and 4 are views in cross-section, taken on the lines 3—3 and 4—4 respectively of Fig. 2;

Fig. 5 is a fragmental view in perspective of the removable point;

Fig. 6 is a similar view of the front portion of the tooth base with which the point, 70 aforementioned, engages;

Fig. 7 is a detail view, in section, illustrating the manner in which the point is 75 assembled upon the base.

Referring to the drawings, wherein similar reference numerals designate corresponding parts throughout, a base 7 is provided with the usual enlargement at its front extremity, forming the nose 8, which is slotted 80 as at 9, for the reception of the front wall of a dipper bucket. A removable point 10 is provided with the rearwardly diverging, upper and lower jaws 11—12, which are adapted to fit against the similarly inclined 85 faces 13, 13' of the nose of the base.

The excessive weight, which is brought to bear upon the front extremity of the tooth point, tends to force the upper jaw 11 away from the inclined face 13' of the 90 nose, and, in order to prevent this, the upper jaw is provided with an elongated dovetailed or undercut lug 14, the same projecting a substantially uniform distance from the inner face of the jaw and extending 95 longitudinally thereof and preferably disposed along the median line. The upper inclined face 13' of the nose is provided with the longitudinally extending undercut or dove-tail shape slot 15, extending throughout the entire length thereof, and so formed as to receive the lug 14 therein when the lug is moved in an endwise direction with respect to the slot, and prevent its direct outward disengagement therefrom. 100

The lower jaw 12 of the point is provided 105

upon its inner face with the outstanding elongated lug 16, of substantially uniform cross-section throughout, the same being adapted to snugly fit within a recess 17, provided therefor within the nose 8. In this connection, it is to be noted that the recess 17 does not extend to the extremity of the nose, but stops a distance therefrom, the point being assembled or secured upon the nose in a manner as illustrated in Fig. 7. The lugs 14 and 16 co-act in holding the point against side or lateral movement, while the spreading of the jaws is rigorously prevented by the securement of the upper jaw 11 to the tooth nose at a point adjacent the extremity of the former. The upper jaw 11 therefore terminates adjacent the extremity of the upper inclined surface 13' of the nose of the base.

20 The lower jaw 12 of the point extends along the lower surface of the enlarged portion of the base, and is provided with the bolt openings 18, which are adapted to register with the similarly disposed openings 19 extending through the base, thus providing for the reception of suitable securing bolts, whereby the lower jaw of the removable point is rigidly secured to the tooth base. The rear portion of the tooth base is also provided with a number of bolt openings 20 which are adapted to receive bolts therethrough, which, in connection with the bolts which pass through the openings 19, are adapted to rigidly secure the tooth to a dipper bucket or analogous structures. The point is cored, as at 21, in order to lighten the same and the base is cored or slotted, as at 22, for a similar reason. The limited depth to which the slot 15 extends, prevents the nose from being materially weakened, as it would necessarily be, were it completely bifurcated for the reception of a web therein, with which removable points are sometimes equipped.

45 The undercut slot 15 with which the nose of the tooth base is provided, is of uniform depth; and the undercut lug of the upper jaw of the point, being of uniform thickness, provides for the rigid securement and anchorage of the upper jaw of the point throughout practically its entire length, these features being obtained with a minimum weakening of the nose of the base. By combining with the foregoing features a lug 55 upon the lower jaw of the point, which is either of uniform width or tapers toward its outer surface, a most secure anchorage for the point against lateral strains is provided, and the spreading of the two jaws of the point is prevented by the dove-tail lug upon the upper jaw and the rearwardly-extending projection with which the lower jaw is provided.

What I claim is:—

63 1. A base for a dipper tooth comprising

an enlarged front portion with inclined faces forming a nose, the upper inclined face of said nose provided with an undercut slot extending the entire length thereof, the lower inclined face of said nose provided with a longitudinally extending recess of limited extent and terminating short of the front extremity of the lower face.

2. A tooth of the class described, consisting of a base with a nose at the front extremity thereof having inclined faces, the upper inclined face of the nose provided with a slot of substantially uniform depth throughout and substantially dove-tail or undercut in cross-section, and a removable point including rearwardly diverging jaws adapted to seat against the inclined faces of the nose, a lug extending along the under face of the upper jaw of the point, substantially dove-tail or undercut in cross-section and of substantially uniform thickness throughout, and insertible in said slot by endwise movement with relation thereto, the lower jaw of said point provided with a rearward extension adapted to be secured to the base.

3. A tooth of the class described, consisting of a base with a nose at the front extremity thereof having inclined faces, the upper inclined face of the nose provided with a slot of substantially uniform depth throughout and substantially dove-tail or undercut in cross-section, and a removable point including rearwardly diverging jaws adapted to seat against the inclined faces of the nose, a lug extending along the under face of the upper jaw of the point, substantially dove-tail or undercut in cross-section and of substantially uniform thickness throughout, and insertible in said slot by endwise movement with relation thereto, the lower inclined face of the nose provided with a slot therein, and the inner face of the lower jaw of the point provided with a lug directly insertible within said slot in the lower inclined face of the nose.

4. A tooth of the class described, consisting of a base with a nose at the front extremity thereof having inclined faces, the upper inclined face of the nose provided with a slot of substantially uniform depth throughout and substantially dove-tail or undercut in cross-section, and a removable point including rearwardly diverging jaws adapted to seat against the inclined faces of the nose, a lug extending along the under face of the upper jaw of the point, substantially dove-tail or undercut in cross-section and of substantially uniform thickness throughout, and insertible in said slot by endwise movement with relation thereto, the lower jaw of said point provided with a rearward extension adapted to be secured to the base, the lower inclined face of the nose provided with a slot therein, and the inner

face of the lower jaw of the point provided with a lug directly insertible within said slot in the lower inclined face of the nose.

5. A base for a dipper tooth consisting of an enlarged front portion having inclined faces and forming a nose, the upper inclined face of said nose provided with an undercut or dove-tail slot extending lengthwise thereof, with the bottom wall of the slot 10 extending substantially parallel to the said inclined face of the nose, the lower inclined face of the nose provided with a slot extending lengthwise thereof.

6. A removable point for a dipper tooth 15 consisting of a wedge-shape member with

rearwardly diverging jaws, the upper of said jaws provided upon its inner face with a longitudinally extending lug substantially dove-tail or undercut in cross-section and of substantially uniform thickness throughout, 20 the lower jaw provided upon its inner face with a lug extending lengthwise thereof.

Signed at Chicago Heights in the county of Cook and State of Illinois this 8th day of Jan. A. D. 1915.
